UNITED STATES PATENT OFFICE.

WILLIAM D. LUTZ, OF ALLENDALE, NEW JERSEY.

INFLATING DEVICE FOR PNEUMATIC APPARATUS.

1,328,088.

Specification of Letters Patent. Patented Jan. 13, 1920.

Application filed October 19, 1915. Serial No. 56,815.

To all whom it may concern:

Be it known that I, WILLIAM D. LUTZ, a citizen of the United States, residing in Allendale, in the county of Bergen and State 5 of New Jersey, have invented a new and useful Improvement in Inflating Devices for Pneumatic Apparatus, of which the following is a specification.

My invention, which relates to an improvement in apparatus for inflating pneumatic tires, has for one of its objects the provision of means whereby a tire may be quickly and easily inflated. Another object of the invention is to provide an apparatus which is adapted to hold air and gas under compression and which may be easily transported from place to place. With an arrangement of this kind, in the case of a flat tire, instead of having to inflate the tire 10 by a pump as has to be done at the present time, and which is a very strenuous task, my apparatus may be connected up to the tire in a few minutes and the tire inflated without any labor, comparatively speaking, 15 20 25 30 35 40 45 50 55 60 65 70 75 80 85 90 95 100 105 110

These and other objects will be fully pointed out in the following description and the appended claims.

Referring to the drawing, Figure 1 shows my device in sectional elevation; Fig. 2 is an end view of the right hand end of the device; Fig. 3 is a section taken on the line *a—a* of Fig. 1 and looking toward the left; Fig. 4 is a section taken through the line *b—b* of Fig. 1, and looking toward the left.

Referring to the drawing in detail, my invention comprises a metal tube 1, preferably made of steel tubing, and forming what we shall call the explosion chamber, and having a spiral thread 2 cut on the outside thereof throughout practically its entire length, the purpose of the spiral thread being to strengthen the tube and provide sufficient radiating surface. Screwed into this expansion chamber at one end thereof, is a shell plug 3, packing 4 being provided between the explosion chamber and the plug to make an air tight fit. In the outer end of the shell plug 3 is an orifice 5, extending longitudinally of the plug for only part of its length, and adapted to receive another plug 6, which carries the firing pin 7. Extending from the bottom of the orifice 5 and longitudinally of the plug 3 to its inner end is a passage 8 which receives the shell 9 which is to contain the explosive used in the operation of the device. This shell 9 is of the usual construction and needs no further description. It carries a primer 10 which is adapted to be engaged by the firing pin 7 when the latter is moved into 60 operated position. The plug 6 which carries the firing pin 7, is screwed into the plug 3. It has a passageway 11 which is for the reception of the pin 7, this passage-way extending from the bottom of an orifice 65 12 formed on the outer end of the plug 6, through the plug to another orifice 13 which is at the inner end of the plug. Formed on the pin 7 near its inner end is a shoulder or collar 14, this shoulder, as is obvious, 70 being for the purpose of preventing the escape of the pin 7 in a backward direction. Near the outer end of the pin is a spring 15 of slightly larger diameter than the passage 11. This spring, of course, prevents the escape of the pin in the other direction. The plug 6 when screwed into the plug 3 engages the shell 9 to hold the latter firmly in place while the apparatus is being used. Screwed into the other end of 80 the tube or explosion chamber 1 is a tube 15, the inner end of said tube being provided with perforations 16 to permit the escape of gas from the explosion chamber. This tube 15 contains a mineral wool W 85 which filters the gases resulting from the combustion of the explosive. It may contain neutralizing chemicals which would absorb or neutralize deleterious gases resulting from the explosion. A valve plug 18 is 90 screwed into the tube 15 at its outer end. Extending across the inner face of the valve plug 18 is a groove 19. Extending longitudinally through the center of the plug 18 is a passage 20, this passage receiving the 95 stem of a needle valve 21. Extending from the passage 20 near its inner end is another passage 22 leading down to the bottom of the plug 18 until it meets an orifice provided in the bottom of said plug for the reception of a flexible piping P which is to be attached to the valve of the tire to be inflated. A continuous passage is thus provided from the tube 15 to the valve of the tire. A corrugated and perforated strainer 105 17 is provided across the tube 15 near the inner end of the tube 18 when the latter is screwed into place. A gage 23 is connected to the plug 18 and has a passage leading down to the point at which the piping W 110 is connected to the plug. Suitable packing 24 and 25 is provided between the tube 1

and tube 15, and between tube 15 and tube 18, to make the connections perfectly tight. A plug 26 is screwed into the outer end of the plug 18 and forms a stuffing box for the 5 stem of the needle valve. R in Fig. 1 designates a relief valve to prevent too high pressure in the explosion chamber.

The operation of the device is as follows: A loaded shell is inserted in the plug 3, the 10 plug 6 is then screwed into place, the needle valve 21 closed, and the firing pin 7 struck a sharp blow. This fires the shell 9. Now the piping P is screwed into the valve plug 18, its other end attached to the valve of the 15 tire, and the needle valve 21 opened. Gas from the explosion chamber will flow through the perforations 16, through the mineral wool W, strainer 17, passages 20, 22, into the piping P and through it to the tire. 20 The gage 23 shows the amount of pressure in the tire, and when this pressure has risen sufficiently the needle valve is closed again, and such gas as will be left in the expansion chamber may be stored up and used at a 25 later time.

It will thus be seen that I have provided a device which is very easily operated, simple in its make-up and of great value for inflating pneumatic tires. 30 It is to be understood that I do not limit myself to the exact details of structure herein disclosed, as I am aware that persons skilled in the art could make various changes therein without departing from the spirit 35 and scope of my invention.

What I claim is:—

1. An apparatus for confining gas under pressure, comprising a cylinder, a plug having a screw threaded connection with 40 one end of the cylinder, said plug having a cylindrical bore extending therethrough to receive a cartridge, the plug being extended within said cylinder to incase the cartridge substantially throughout its length, and a 45 second plug having a threaded connection with the first plug for closing it and retaining the cartridge therein.

2. An apparatus for confining gas under pressure, comprising a cylinder, a plug having a screw threaded connection with one 50 end of the cylinder, said plug having a cylindrical bore extending therethrough to receive a cartridge and a second plug having a threaded connection with the first plug 55 for closing it and retaining the cartridge

therein, and a firing pin extending through said second plug operable on a primer carried by the cartridge for discharging the latter.

3. An apparatus for confining gas under 60 pressure, comprising a cylinder, a plug having a screw threaded connection with one end of the cylinder, said plug having a cylindrical bore extending therethrough to receive a cartridge, a second plug having a 65 threaded connection with the first plug for closing it and retaining the cartridge therein, a hollow plug having a threaded connection with the opposite end of the cylinder, a valve plug closing the outer end of 70 the hollow plug, a valve in said valve plug to regulate an outlet opening communicating with the interior of the hollow plug, and means in the latter for purifying the gas.

4. An apparatus for confining gas under 75 pressure, comprising a cylinder, means at one end thereof for containing a cartridge, a hollow plug extending into the opposite end of the cylinder and having a threaded connection therewith, said plug having 80 openings communicating with the interior of the cylinder, material in said plug for removing or neutralizing substances in the gas deleterious to the purpose to which the gas is to be put, and means for conducting the 85 gas discharged from the cylinder through the hollow plug.

5. An apparatus for confining gas under pressure, comprising a cylinder, means at one end thereof for containing a cartridge, 90 a hollow plug extending into the opposite end of the cylinder and having a threaded connection therewith, said plug having 95 openings communicating with the interior of the cylinder, material in said plug for removing or neutralizing substances in the gas deleterious to the purpose to which the gas is to be put, a valve controlling the passage of gas through the hollow plug and means for closing the valve to retain the gas 100 in said cylinder and for opening the valve and regulating the rate of flow of gas therethrough.

In testimony whereof I have signed my name to this specification in the presence of 105 two subscribing witnesses.

WILLIAM D. LUTZ.
